Assistant Examiner — Jennylo M Binas

(57) **CLAIM**

The ornamental design for a cosmetic brush cleaning device, as shown and described.

DESCRIPTION

FIG. 1 is a front, top perspective view of a first embodiment of a cosmetic brush cleaning device, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, top perspective view of a second embodiment of the cosmetic brush cleaning device;

FIG. 10 is a rear, and bottom, perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The broken lines in the figures illustrate portions of the cosmetic brush cleaning device that form no part of the claimed design.

1 Claim, 16 Drawing Sheets
